UNITED STATES PATENT OFFICE.

CHARLES M. HICKEY, OF NEW YORK, N. Y.

SAFETY RAZOR.

Application filed September 28, 1927. Serial No. 222,603.

This invention relates to safety razors, and has for an object to provide an improved construction wherein a double edge blade may be used, but only one edge in operative position at a time.

Another object of the invention is to provide a safety razor wherein a plurality of means are provided for clamping a blade in operative position.

10 An additional object is to provide a safety razor wherein the guard may be swung to an inoperative position when one edge of the blade is to be stropped.

In the accompanying drawing—

15 Figure 1 is a plan view of a safety razor disclosing an embodiment of the invention, part of the handle being broken away.

Figure 2 is a rear edge view of the structure shown in Figure 1.

20 Figure 3 is a sectional view through Figure 1 on line 3—3.

Figure 4 is a transverse sectional view through Figure 1 on line 4—4.

25 Figure 5 is a plan view of a sliding clamp embodying certain features of the invention.

Figure 6 is a bottom plan view of the operating parts of the razor shown in Figure 1, the guard being shown in a reversed or inoperative position.

30 Figure 7 is a view similar to Figure 6 but with the guard in an operative position.

Figure 8 is a detail sectional view through Figure 2 on line 8—8.

35 Figure 9 is a plan view of the blade used in the razor shown in Figure 1.

Referring to the accompanying drawing by numerals, 1 indicates the shank of a razor and 2 a handle which is pivotally mounted on the shank 1 by suitable pivotal means. 3. The 40 handle 2 may be of any desired or usual structure adapted to swing over the remaining part of the razor for protecting the same in the usual manner. The shank 1 merges into what may be termed a slotted neck 4 having a slot 5 accommodating the pivot pins 6 and 7 carried by the turned down ears 8 and 9 of the sliding clamp 10. The sliding clamp 10 is provided with square openings 11 and 12, each of said openings merging into a laterally 45 extending slot 13. The neck 4 merges into what may be termed the body 14 of the razor, which body is comparatively thin and flat except at the rear edge, which is widened by laterally extending flanges 15 and 16. These 50 flanges extend a sufficient distance to give the proper honing and stropping angle to the re-

spective edges of the blade 17. The blade 17 is rectangular and provided with cutting edges 18 and 19 and apertures 20 and 21. Body 14 is provided with two pairs 60 of turned up ears 22, each ear of each pair having a turned over retaining flange 23. Each pair of ears 22 is formed so as to easily pass through the apertures 20 and 21 in blade 17 so that the blade may be forced 65 flatwise against the body 14. After this has been done, the sliding clamp 10 is slid from the dotted position shown in Figure 2, over to almost the full line position, and then swung downwardly until the ears 22 extend 70 through the apertures 11 and 12. After this has been done, the clamping member 10 is given a further sliding movement away from handle 2, and when this is done, the flanges 23 will slide over the portions of clamp 10 on 75 each side of the slots 13. As the ears 22 are somewhat resilient, as well as the flanges 23, the movement of the parts to the position just described, will produce the desired resilient clamping action for clamping the blade 80 17 firmly in place, as well as the clamping member 10.

Arranged on the opposite side of the body 14 to the blade 17, are slightly raised portions 24 and 25, said raised portions having sockets 85 therein for accommodating the integral journal pins 26 and 27 formed on the guard 28. This guard is provided with suitable fingers 29 which produce the desired guarding action when the parts are in the position shown in 90 Figure 7. Guard 28 is provided with a slot 30 through which a flat spring 31 extends, said spring having the rear portion 32 clamped rigidly to the body 14 by screws 33. Slot 30 is slightly wider than the thickness 95 of the spring 31 and is also slightly longer. This will permit a sufficient longitudinal movement of guard 28 to permit the journal pin 26 to be inserted into the socket in lug 24 a sufficient distance to permit journal pin 100 27 to pass lug 25. After this has been done, the guard is moved back so that the pin 27 will move into the socket in lug 25, but this socket is so shallow that pin 26 will not move 100 out of the socket of lug 24.

When the parts are mounted as just described, the guard may be swung to the position shown in Figure 6 and held in that position by spring 31, or may be swung to the position shown in Figure 7 and be held 110 in that position resiliently by spring 31. When in the position shown in Figure 7, the

razor is in condition for use. At any time the guard 28 may be swung to the position shown in Figure 6 and the edge of the blade 7 stropped in the usual manner. After stropping, the guard is swung back to the position shown in Figure 7 and the parts are in operative position. After having been used, the razor may be rinsed off, the blade 17 removed and the various parts dried if desired.

- 10 In order to remove the blade 17, the clamping member 10 is slid longitudinally from the position shown in Figure 2 toward the right until the apertures 11 and 12 accommodate the respective ears 22. Clamp 10 may then 15 be swung upwardly further back out of the way, after which the blade 17 may be raised off of body 14. It will thus be seen that the blade may be quickly applied or removed at any time, and that the guard is normally left 20 in place but may be swung to a position guarding the blade or to a position permitting honing of the blade.

What I claim is:

1. A safety razor, comprising a body 25 formed with a neck and with a plurality of upstanding resilient ears formed with flanges, a blade having apertures of a size whereby the blade may be placed on said body so that said ears will project through said apertures, a 30 swinging clamp carried by said neck formed with apertures for permitting the clamping member to move over said ears, each of said last mentioned apertures having a restricted neck whereby when said clamping member is 35 moved longitudinally the portions adjacent the neck will move beneath the flanges on said ears for producing a clamping action, and a guard arranged on said body on the opposite face to the blade.
- 40 2. A safety razor, comprising a body formed with laterally extending flanges on one edge, a neck extending from one end of the body formed with grooves on opposite faces, said neck merging into a shank, a 45 handle pivotally mounted on said shank, said body being provided with a pair of pressed up portions acting as ears, each of said ears having a turned over flange, a blade formed with a pair of apertures accommodating said ears 50 when the blade is in position against said body, a clamping member formed with a body having a pair of apertures and a restricted notch extending from each aperture, said body at one end being formed with a pair of 55 ears, journal pins extending from said ears into said neck whereby the clamping member is pivotally and slidably mounted, said clamping member being adapt-

ed to be pivotally and slidably moved to a position so that the ears will project through the apertures in the body of the clamping member and then move until the ears are fitted into said notches, a guard pivotally mounted on said body on the opposite side to said blade, said guard being swingable so as to overlap either edge of said body, and a flat spring extending loosely through said guard, said spring acting to resiliently lock the guard in either of two positions.

3. In a safety razor, a flat body formed 70 with a neck extending therefrom having grooves in opposite faces, a blade fitted against said body and clamping means for clamping said blade in place, said clamping means including a clamp adapted to fit flat-wise against said blade, a pair of ears at one end, and journal pins extending through said ears into said grooves whereby the clamping member may move pivotally and may slide longitudinally of the neck.

4. In a safety razor, a body having a slotted shank, a blade positioned on the body and extending from one edge of the body, means for removably clamping said blade on the body, a guard means including a pin extending 85 through the slot in said shank for pivotally mounting said guard on said body and overlapping part of the blade, and spring means for resiliently holding the guard in place.

5. In a safety razor, a body, a blade fitted 90 on the body, means for clamping the blade in place, a guard pivotally mounted on one face of said body, said guard being formed with a slot, and a flat spring rigidly secured to said body continually extending through said slot 95 and acting to resiliently lock the guard in either of two positions, said guard being adapted to be swung to overlap one edge of the blade and swung to an operative position away from the blade.

6. In a safety razor, a body formed flat except on one edge, said body being formed with a slotted shank and a plurality of pairs of bent up ears, each ear having a flange, a blade formed with openings whereby the same may be pinched over said pairs of ears and raised flatwise against the body, and clamping means interlocking with said flanges for clamping said blade in position, said clamping means including a pin extending through said slotted shank for pivotally mounting said clamping means on said shank.

Signed at New York, in the county of New York, and State of New York, this 26th day of September, A. D. 1927.

CHARLES M. HICKEY.
